CONTAINER

Christian Lee Graber, Lakewood, Ohio

Application April 10, 1935, Serial No. 15,660

5 Claims. (C.I. 128—214)

The present invention relates to containers or flasks for medical liquids or solutions, and more particularly to containers or flasks for shipping and storing solutions used in intravenous therapy.

An object of the present invention is the provision of a novel container or flask for medical liquids, especially solutions used in intravenous therapy.

Another object of the present invention is the provision of a novel container or flask for medical liquids, especially solutions used in intravenous therapy, of improved construction which will be convenient to handle and use, and which will maintain the liquid or solution contained therein for extended periods and prevent any probability of infection or contamination.

The invention resides in certain novel details of construction and arrangements and combinations of parts, and further objects and advantages thereof will be apparent from the following description of the preferred embodiment thereof described with reference to the accompanying drawing, in which

Fig. 1 is an elevation, with portions in section, of a flask embodying the present invention;

Fig. 2 is a view of the flask shown in Fig. 1 supported for use;

Fig. 3 is a plan view of the flask shown in Fig. 2;

Fig. 4 is a view on the line 4—4 of Fig. 1;

Fig. 5 is an enlarged section of the lower end of the flask as shown in Fig. 1, taken approximately in the plane of the paper;

Fig. 6 is an enlarged elevation of the lower end of the flask as shown in Fig. 1, looking from the right; and

Fig. 7 is a view showing a modified construction of the flask shown in Fig. 1.

Referring to the drawing, the preferred embodiment of the invention illustrated comprises a container made of heat-resistant comparatively alkali-free glass, designated in general by the reference character A. The container A comprises a body portion 10 of generally cylindrical shape, the opposite ends of which are constricted to form elongated reduced extensions or necks 11 and 12.

The body portion 10 of the flask illustrated, which is preferably made oval-shaped or the like to prevent the same from rolling when laid on a flat surface, such as a table, has a capacity slightly greater than a liter and is graduated in cubic centimeters for a purpose which will be readily apparent.

The upper or filler neck 11 is preferably used for filling the container, the outside surface

thereof being provided with screw threads formed in the glass for the retention of a closure or cap designated generally by the reference character B. The cap B comprises a tubular or cup-shaped member 15 closed at one end and preferably made of metal, Bakelite, or the like, adapted to be screwed onto the threaded portion of the filler neck 11 provided with a plurality of projections extending radially therefrom, either formed integrally therewith or, as illustrated, in the form of an elongated member 16 secured to the upper closed end of the cup-shaped member 15 in some convenient manner, such as by spot-welding, etc. in the event the cap is made of metal. In addition to serving as a hand grasp for the member 15, the member 16 provides a means for suspending the flask when in use. In the preferred embodiment, the flask is adapted to be suspended from a hook 19 or the like through the medium of a bail in the form of a string 20 secured to opposite ends of the rectangular member 16. A washer 21 positioned in the closed end of the opening in the member 15 provides a seal for the end of the neck 11 and prevents the contents of the flask from coming in contact with the member 15.

The lower or outlet neck 12 is preferably tapered to facilitate the attachment of different sized tubing thereto, and the exterior surface thereof is preferably provided with alternate ridges and furrows which assist in holding the tubing thereon. As illustrated, the lower end of the aperture 23 extending through the neck 12 is closed by a stopper 25, preferably of rubber, formed integral with the closed lower end of a tubular member 26 also preferably made of rubber or rubber substitutes. The tubular member 26 projects up over the exterior surface of the neck 12 to a point adjacent the body portion where it is preferably folded back on itself for a short distance. In addition to forming a closure for the lower end of the container, the members 25 and 26 prevent contamination of the neck 12 during shipment, handling preparatory to use, etc.

To facilitate removal of the member 26 and the stopper 25, a string 28 or the like is secured around the lower end of the stopper 25 prior to the positioning of the member 26 about the neck. When the member 26 is placed in position, the string 28 extends up along the neck preferably underneath the same, as shown. The string 28 preferably folds back on itself as at 29 and passes through the upper edge of the member 26 as at 30 to facilitate removal of the

same. The string 28 is again folded on itself as at 31, and a dust seal 32 in the form of some suitable material, such as paper, etc., placed about the neck 12 overlapping the member 26. 5 The dust seal among other things indicates to the user whether or not the lower end of the flask has been previously opened or tampered with in a manner which might result in contamination of the contents. While the preferred construction has just been referred to, it is to be understood that the string 28 could be projected through the member 26 at the lower end thereof, in which event the string would be extended up along the neck over the member 26 and secured to the upper edge thereof in some convenient manner.

Provision is also made for preventing rotation of the closure B in a direction to remove the same, except a slight amount for the admission 20 of air during use, in the form of a member secured to the body portion 10 and the closure B. As illustrated, one end of the string 20 is extended and secured to the body portion 10 by a sticker or tab 35, but it is to be understood other 25 suitable means may be employed, such as attaching the end of the string to a projection or eye formed integral with the body portion 10. Both ends of the string 20 may be extended and secured to eyes formed on opposite sides of the 30 body portion 10, if desired. In order to make sure that the washer 21 disengages the upper end of the neck 11 when the closure B is unscrewed, the same is secured to the member 15 in some convenient manner, as by a plurality of projections or depressions formed in the member 35 15 which engage the washer without puncturing the same. A dust seal 36 similar to the dust seal 32 previously referred to is placed about the filler neck 11 and the member 15 to prevent entrance of dirt, etc. underneath the cap. 40

The flask is shipped in the condition illustrated in Fig. 1, and when it is desired to use the same, the body portion 10 is grasped with one hand while the other pulls the string 28, removing first the member 26 and subsequently the stopper 25 without disturbing the sterilized condition of the lower or outlet neck 12. After a hose 38 has been attached to the outlet 12, the flask is turned to an upright position and the closure B turned until the string 20 becomes taut. Thereafter the flask is suspended from some suitable support. During use, air is admitted to the upper end of the flask around the neck 11 underneath the member 15, which construction assists in preventing contamination of the contents by the incoming air.

A modified construction of the means previously referred to for preventing complete removal of the cap B is illustrated in Fig. 7, where- 60 in the similar parts are designated by the same reference characters with a prime mark affixed thereto. The container A' is the same in construction as the container A previously described, with the exception of the fact that it is provided 65 with a projection 40 preferably formed integrally therewith. The cap B' is similar in construction to the cap B with the addition of a washer or ring-shaped member 41 secured thereto and the elimination of the end of the string 20 which is 70 adapted to be secured to the container. The member 41 carries a projection 42 detachably secured thereto adapted to engage the projec- 75 tion 40 and thereby limit the rotation of the cap B' to one turn or less. As illustrated, the pro- jection 42 is in the form of a screw adapted to

be threaded into one of a plurality of tapped apertures in the member 41 and sealed therein after the cap B' has been secured in position.

From the foregoing description of the preferred embodiment of the invention, it will be apparent that a new and improved container or flask for medical solutions, especially solutions used in intravenous therapy, has been provided. The flask of the present invention will preserve the contents indefinitely, and can be conveniently used without presenting any problem of sterilization just before using, and, with reasonable care, without probability of contamination.

The preferred embodiment of the invention has been illustrated and described, but it is not my intention to be limited to the particular construction shown which may be varied within the scope of the invention. While the capacity of the flask shown is approximately one liter, it is to be understood that the same may be made in any desired capacity. The present application is intended to cover all adaptations, variations, and uses as come within the knowledge and customary practice of those skilled in the art to which it pertains, and I particularly point out and claim as my invention the following:

1. In a flask for medical solutions used in intravenous therapy, the combination of a container comprising a body portion having a reduced extension or neck at one end thereof provided with an aperture extending therethrough and adapted to receive a rubber tube, a closure for said extension or neck comprising an elastic tubular member closed at one end positioned over said extension, a stopper secured to the interior 30 of the tubular member at the closed end thereof projecting into the aperture in said extension or neck, and means secured to said stopper and extending along the extension or neck at opposite sides thereof adapted to remove the tubular 35 member and stopper.

2. A flask for medical solutions used in intravenous therapy comprising a transparent body portion, a reduced extension or neck at the upper end of said body portion, a cap-like member positioned over said reduced extension or neck for closing the same, means for limiting the removal of said cap-like member from said reduced extension or neck, a second reduced extension or neck at the lower end of said body portion 45 adapted to receive a rubber tube or the like, and a cap-like member positioned over said second extension or neck for closing the same, said cap-like member being formed of elastic material and being adapted to be removed from said second 50 extension or neck by having the open end thereof at least partially pulled or rolled back over itself.

3. A flask for medical solutions used in intravenous therapy comprising a transparent body portion, a reduced extension or neck at the upper 60 end of said body portion, a cap-like member positioned over said extension or neck and having threaded engagement therewith for closing the same, means for limiting the rotation of said cap-like member in a direction to remove the same 65 from said extension or neck, a second reduced extension or neck at the lower end of said body portion adapted to receive a rubber tube or the like, an elastic tubular member closed at its lower end positioned over said second extension for 70 closing the same, said elastic tubular member being adapted to be removed from said second extension or neck by having the open end thereof at least partially pulled back over itself, and means constituting a hand grasp connected to 75

said tubular member for removing the same from said second extension or neck.

4. A closure for an extension or neck of a flask or container adapted to have a delivery tube attached thereto, said closure comprising an elastic tubular-shaped member closed at the lower end adapted to fit over the end of the extension or neck of the container and flexible means adapted to be grasped so that the same can be removed from the extension or neck by being at least partially rolled or pulled back on itself without the hands coming in contact with the extension or neck.

5. A flask or container for medical solutions used in intravenous therapy comprising a body

portion having an opening at the upper end, a closure member for the upper end of said body portion, a reduced extension or neck at the lower end of said body portion adapted to have a delivery tube attached thereto, and a closure for said reduced extension or neck comprising an elastic tubular-shaped member closed at the lower end and adapted to fit over said extension or neck and flexible means adapted to be grasped so that the same can be removed from the extension or neck by being at least partially rolled or pulled back on itself and without the hands coming in contact with the extension or neck.
